UNITED STATES PATENT OFFICE.

ABRAHAM C. FISHER, OF NEW YORK, N. Y.

DESIGN FOR A LADY'S VANITY-CASE.

55,852.

Specification for Design.

Patented July 20, 1920.

Application filed March 13, 1920. Serial No. 365,640. Term of patent 3½ years.

To all whom it may concern:

Be it known that I, ABRAHAM C. FISHER, a citizen of the United States, and a resident of the borough of Manhattan, in the county, city, and State of New York, have invented a certain new, original, and ornamental Design for Ladies' Vanity-Cases, of which the following is a specification.

My new design is illustrated in the accompanying drawing, in which—

Fig. 2 is a side view, and
Fig. 3 is an end thereof.

I claim:

The ornamental design for a lady's vanity case, substantially as shown.

ABRAHAM C. FISHER.
